Maurice S. Sussman

UNITED STATES PATENT OFFICE

ARTHUR VON FRANKENBERG, OF NEW YORK, N. Y., ASSIGNEE TO FRANKART, INC.,
OF NEW YORK, N. Y., A CORPORATION OF NEW YORK

DESIGN FOR AN ASH TRAY OR SIMILAR ARTICLE

Application filed May 26, 1930. Serial No. 35,772. Term of patent 14 years.

To all whom it may concern:

Be it known that ARTHUR VON FRANKENBERG, citizen of the United States, and resident of New York city, in the county of New York and State of New York, has invented a new, original, and ornamental Design for an Ash Tray or Similar Article, of which the following is a specification, reference being had to the accompanying drawing, forming part thereof, in which the figure is a perspective view of an ash tray embodying my new design.

I claim:

The ornamental design for an ash tray or similar article, substantially as shown.

Dated, New York city, May 21, 1930.

ARTHUR VON FRANKENBERG.
